GRINDING AND METAL DISINTEGRATING APPARATUS

Clifford L. Garrison, Adrian, Mich., assignor to Oliver Instrument Company, Adrian, Mich., a corporation of Michigan

Filed Oct. 6, 1960, Ser. No. 60,953
20 Claims. (Cl. 204—217)

This invention relates to metal disintegrating and grinding machine and more particularly to an apparatus for removing metal from form cutters or multitoothed cutting tools where it is essential that the teeth of the cutting instrumentality be shaped or conformed to a uniform size or standard.

Cutter grinders have been devised and used for grinding teeth of rotatable cutting instrumentalities, tools or multitoothed cutters by reciprocating a ram carrying a rotating grinding wheel in engagement with successive teeth of a cutter, the path of the abrading region of the wheel being controlled by a pattern or template associated with the ram. A grinding machine of this character is illustrated in Oliver Patent 2,055,361. The components of the grinding apparatus illustrated in this patent are mechanically operated through mechanical power transmission means from two sources of power.

The present invention embraces apparatus for conforming or sharpening cutting tools or instrumentalities by electrically disintegrating metal of the teeth of a cutting tool or instrumentality or abrading metal of the teeth to a predetermined pattern or size.

The present invention has for an object the provision of apparatus embodying a rotary metal disintegrating electrode in an electrical circuit which is reciprocable across the multitoothed cutting tool or work piece in conjunction with a reciprocable support for the metal disintegrating electrode controlled by cam means, and wherein the electrode is moved across the work piece at a comparatively low speed during an operative or metal disintegrating stroke of the electrode and the stroke speed increased during idle range of movement of the electrode whereby the time required to perform metal disintegrating or tooth shaping operations on a multitoothed tool or cutter is greatly reduced.

Another object of the invention resides in an electric metal disintegrating system or apparatus, especially adaptable for conforming teeth of a multitoothed cutter wherein in each tooth comprises two or more cutting edges in angular relation and wherein one cutting edge is acted upon by electric current through the medium of the metal disintegrating instrumentality in one direction of movement thereof, and another cutting edge of the tooth acted upon by current through the metal disintegrating instrumentality during a retractive stroke of the latter whereby to accurately conform both edges of each tooth by independent movements of the metal disintegrating electrode.

Another object of the invention is the provision of an apparatus for electrically disintegrating or abrasively removing metal of the teeth of a cutter or tool through a hydraulically controlled system whereby the effective metal disintegrating or abrading strokes of the member are effected at proper speeds to attain most efficient metal disintegration or removal in sharpening or conforming the teeth of a cutter.

Another object of the invention resides in an improved means for effecting relative movement between the cutter or work piece being operated upon and the metal disintegrating or abrading means for regulating or controlling the amount of metal removed during an operative cycle of the metal disintegrating or abrading means.

Another object of the invention embraces a control

2

system for a multitoothed cutter grinding apparatus wherein the cutter is automatically indexed to bring successive teeth thereof into position to be acted upon by the grinding or abrading means and wherein the apparatus is automatically brought to rest after all of the teeth of the cutter have been ground or conformed to a desired shape or pattern.

Another object of the invention resides in a hydraulically operated means for elevating the ram of the cutter tool processing apparatus to facilitate the interchange of templates or pattern blocks for conforming the teeth of different types and sizes of cutters or cutting tools to desired shapes.

Another object of the invention resides in an improved means for positively lubricating a reciprocating component of a toothed cutter processing apparatus.

Another object of the invention is the provision of an apparatus for conforming or sharpening multitoothed cutters through the utilization of a rotating component in conjunction with electric energy conducted through the rotating component whereby the resistance to the passage of current at a region of the rotatable component adjacent a cutter effects a controlled disintegration or removal of the adjacent metal of the cutter to effect a sharpening or forming of the cutter teeth to a predetermined shape or pattern.

Another object of the invention resides in a cutter mounting and indexing means for automatically advancing a cutter after each cycle of metal disintegrating or abrading operations have been performed upon a cutter tooth until all teeth of a cutter have been processed and the apparatus automatically brought to rest.

Another object of the invention resides in an electric metal disintegrating system or method wherein a rotatable and reciprocable arbor provides a current conducting component for current supplied through a rotating instrumentality or electrode carried by the arbor and controlling the path of the rotatable instrumentality during flow of electrical energy therethrough for removing metal of a tool for sharpening the tool.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

FIGURE 31 is a sectional view lengthwise of the ram illustrating the cam controlled path of a metal removing wheel in cutting or sharpening teeth of a multitoothed rotary cutter;

FIGURE 32 is a graphic representation of the duration of the relatively fast and slow speed periods of travel of the ram in a cycle of removing metal from a tool by electric disintegration, and

FIGURE 33 is a fragmentary view of a cutter tooth processed or sharpened through the use of the apparatus of the invention.

The method and apparatus of the invention are especially usable for disintegrating, grinding or abrading metal of work pieces, such as multitoothed cutters, for accurately conforming or sharpening teeth of cutters to a desired standard, the apparatus of the invention being usable with a wheel of abrasive material for removing metal by abrasion or usable with an electric current conducting wheel or rotatable electrode for electrically disintegrating or removing metal from a work piece or cutter through electrolytic action.

Referring to the drawings in detail and initially to FIGURES 1 and 2 the apparatus illustrated therein is especially adaptable for grinding cutters or tools through the medium of an abrasive grinding wheel but is adaptable, with certain modifications hereinafter pointed out, for processing or removing metal from cutter teeth or other work piece by electric disintegration through electrolytic

action. The apparatus is inclusive of a hollow base, support or frame 10 formed of cast metal and upon which are mounted the several components of the grinding or cutter processing apparatus.

5 The base or frame 10 supports a plate or platform 12 provided with longitudinally extending ways supporting a carriage or standard 14 which supports the reciprocable ram for the grinding wheel ram and associated mechanism, the platform 12 being fixedly secured to the base frame 10.

The plate or platform 12 is provided with a depending bracket 16 in which is revolvably mounted a bushing-like member 17 interiorly threaded to receive the threaded portion 18 of a shaft 19 which extends through a boss 20 15 formed on the base 10 and is fixedly connected with a member 22 secured to and depending from the bracket 14.

The nut or bushing 17 is fashioned with a toothed or worm gear portion 24 which meshes with a worm wheel 26 mounted upon a transversely extending shaft 28 which 20 projects through an opening in the side wall of the base and is equipped with a hand wheel 30, shown in FIGURE 2, for adjusting the ram supporting bracket or carriage 14 lengthwise of the base 10. In the embodiment illustrated in FIGURES 1 and 2, the carriage 14 forms a support 25 upon which is pivotally mounted a reciprocable ram construction for moving a rotating grinding or metal removing wheel relative to the work piece or cutter.

The bracket or carriage 14 is provided with a transversely extending pivot shaft or trunnion 34 journaled in 30 bearings 35 upon which is pivotally supported a housing or supplemental frame 36 which is oscillatable or swingable about the axis of the trunnion shaft 34. The housing or supplemental frame 36 is formed with interior planar bearing surfaces or ways in which is reciprocably 35 mounted a ram 40 of hollow or tubular configuration and preferably generally rectangularly shaped in cross-section.

The hollow interior of the ram 40 accommodates power transmission means for rotating a grinding or metal disintegrating wheel. Fixedly secured at the rear end of the ram 40 is a fitting or bracket 42 fashioned with a platform 44 supporting an electrically energizable motor 46 for rotating the grinding wheel. Formed integrally with the fitting 42 is a hollow boss 48 in which is journaled a shaft 50 provided at one end with a sheave or pulley 52. The shaft of the motor 46 is provided with a driving sheave or pulley 54 which, through the medium of belts 56 rotates the shaft 50.

The forward end of the ram 40 is equipped with a fitting 60 provided with vertically disposed ways (not shown) in which is slidably mounted a head 64. The head 64 supports a fitting or bushing 66 formed with a flange 68 secured to the head 64. The head 64 is arranged to be moved by automatic means to establish a feed for dressing the grinding wheel by engaging the wheel with a truing 55 tool or diamond at each stroke of the ram.

The bushing 66 is provided with antifriction bearings journaling supporting a shaft 69 of a hub assembly 70 which provides a mounting for a rotatable member, grinding wheel or instrumentality 72 effective to remove metal from, contour or sharpen machine tools or cutters, such as those of the multi-toothed type shown at C in FIGURE 32.

The shafts 50 and 9 are connected with universal joints 73 and 74 respectively, the universal joint 73 being provided with a rod-like extension 75 which telescopes into a tube or sleeve 76, the tube having a projection 77 extending into a groove in the extension 75 to establish a drive connection between the shafts 50 and 69.

The universal joints 73 and 74 and the telescoping connection of extension 75 with sleeve 79 facilitates relative vertical movement of the head 64 during reciprocatory movements of the ram while maintaining a drive connection between the motor 46 and the wheel 72. In the embodiment illustrated in FIGURE 1, the head 64 is provided with a tubular portion 32 connected by means of a

flexible tube 83 with a section blower or other means for conveying away abraded or disintegrated metal particles removed from the work piece or cutter and abrading material of the wheel.

The automatic feed mechanism for vertical progressive movement of the head 64 with respect to the fitting or support 60 for dressing the wheel will be hereinafter further described in detail. A flexible accordion-like bellows 86 is connected between the member 60 carried by the ram 40 and the forward end portion 87 of the pivotally mounted supplemental frame or bracket 36 to prevent the ingress of foreign matter or particles of metal into the region of the drive mechanism for the wheel 72. A similar bellows 89 is connected between the motor support 42 and the rear end of the supplemental frame 36 for the same purpose.

The ram 40, the motor 46 and associated drive mechanism, the head 64 and the wheel 72 are adapted to be reciprocated relative to the supplemental frame or carriage 36 by hydraulic means. Disposed above the ram 40 is a member or block 92 formed with a cylindrical bore 93 fitted with end heads 94 and 95. The end head 94 is provided with an opening provided with a stuffing gland accommodating a piston rod 97, one end of which is anchored or secured to the motor support 42, as shown in FIGURE 1, the other end extending into the cylinder 93 and provided with a piston 98 reciprocable in the cylinder.

The member 92 is provided with a fitting 100 which supports a control valve 102 manipulated by a handle 104 which is adapted to control delivery of fluid under pressure for reciprocating the piston 98 and the components connected therewith. The control member 102 initiates or admits flow of fluid to a valve mechanism hereinafter described for securing continuous automatic reciprocation of the piston 98 when the valve 102 is in open position in a manner hereinafter explained.

The base or frame 10 of the machine supports a means for mounting a multitoothed cutter C, shown in FIGURE 31, or other tool to be ground, sharpened or conformed to a predetermined pattern. With particular reference to FIGURES 1 and 2, a vertical wall of the base 10 is fashioned with a transversely extending enlargement or boss 110 provided with a transverse recess accommodating a tang or projection 112 formed upon a cross slide or transversely slidable support 114.

The cross slide 114 is provided with vertically arranged portions 116 provided with pairs of slots 118 and 119 accommodating securing screws 120 which may be drawn up to anchor the cross slide 114 to the base frame 10 after adjustment of the cross slide has been made. The member 114 is provided with plates 115 which form vertical ways in which is slidably mounted a housing 124 having a hollow interior, as shown in FIGURE 1.

Disposed within the housing 124 are antifriction bearings 126 and 128 in which is journally supported a work supporting spindle or arbor 130. The upper end of the arbor 130 is provided with a disc-like table 132 upon which a work piece or cutter C, shown in FIGURE 31, is adapted to be mounted during grinding or cutter-contouring operations. The arbor 130 is provided with a tenon 134 and a collar 135 for centering a cutter on the arbor. A clamping disc 136 and a clamping screw 137 are provided for securely anchoring the cutter or work piece on the table 132. Other suitable means for anchoring or mounting the cutter may be employed.

Means is provided for elevating the work supporting arbor 130 and its housing 124. Secured to a wall of the housing 124 is a tubular extension 140, shown in FIGURE 2 in which is journally supported a shaft 142, shown in FIGURE 1, a manipulating hand wheel 143 being secured to an end of the shaft projecting from the tubular support 140. Mounted on the shaft 142 is a worm gear 144 which meshes with a driven gear 146 secured upon

a vertically disposed shaft 147 journalled in bearings provided in a portion of the housing 124.

The shaft 147 is provided with a threaded portion 148 which is threaded into a block or member 149 secured to the cross slide 114. Rotation of the hand wheel 143 effects rotation of shaft 142, worm gear 144, driven gear 146 and the screw 148 to elevate or lower the housing 124 and the work piece or cutter support carried thereby.

The apparatus is inclusive of means for indexing or rotating the cutter supporting arbor 130 to bring successive teeth of a cutter into position with respect to the grinding or metal disintegrating wheel 72 to effect grinding operations successively upon the cutter teeth. Secured to the housing 124 is a casing or gear box 150. Journalled in bearings in the casing 150 is a transverse hollow shaft 152. Loosely mounted upon the shaft 152 and restrained against endwise movement are bevel gears 154 and 155. Slidably mounted upon the shaft 152 and adapted to rotate therewith under the influence of pins 150 are clutch members 156 and 157, shown in FIGURE 2, adapted for rotation with the shaft 152 but are slidable along the shaft.

The clutch member 157, as shown in FIGURE 2, is in clutching engagement with the gear 155, the clutch member 156 being adapted for slidable engagement to also effect clutching engagement with the gear 154. Mounted upon the lower end of the work supporting arbor 130 is a bevel gear 160 adapted to be selectively engaged by gear 154 or gear 155 to obtain an indexing movement of the work supporting arbor 130 in either direction.

The shaft 152 is hollow or tubular to accommodate a clutch operating shaft (not shown) which is provided with a manipulating means 162 for shifting the clutch operating shaft to selectively move clutch member 156 or clutch member 157 into clutching engagement with gear 154 or gear 155 to drive the bevel gear 160 and arbor 130 in one direction or the other.

Fixedly secured on the transverse shaft 152 is a gear 164 which meshes with a driving worm 166 journalled within the gear box 150. The gear 166 is loosely journalled upon a shaft 168. Secured on a countershaft 170 is a gear 172 enmeshed with the gear 166. A spur gear 174 secured on the countershaft 170 is enmeshed with a spur gear 176 secured upon the shaft 168. The shaft 168 is connected with a universal joint 178, one component 179 of the universal joint 178 having a spline connection with a shaft or component 180 of a second universal joint 182.

Supported by the base 10 is housing 184 in which is journally supported a shaft 186 connected with the universal joint 182, as shown in FIGURE 1. Mounted upon the shaft 186 are members 188 and 190 which are actuated by means hereinafter described for effecting successive indexing movements of the work piece or cutter supporting arbor 130.

A suitable braking or friction means is provided for the work support 130. As shown in FIGURE 1, a friction band 143 engages the spindle or work support 130 and is adjustable by an adjusting screw 145 to regulate the amount of friction to reduce lost motion or prevent "over-run" of the spindle or work support 130.

A current conducting shoe or brush 158 engages a bronze ring 159 and a current conducting cable 161 connected with the brush 158 forms a circuit for the electrolytic metal disintegration system hereinafter described.

The work supporting spindle 130 is insulated from its casing 124 by means of insulating sleeves 167 and 169, the latter sleeve being held in place by a fiber ring 171 as shown in FIGURE 19. The bevel gear 160 is made of fiber or other insulating conducting material when the apparatus is used for electrolytic metal disintegration.

Through this arrangement the work support 130 and the work carried thereby are insulated from the housing 124 of the apparatus.

Several components of the apparatus are actuated by fluid pressure such as oil for a force transmitting medium. As shown in FIGURE 1, there is mounted upon the base

10 a receptacle 194 adapted to contain a supply of oil or other fluid. Secured to wall 195 of the receptacle is a pump 196, of the conventional rotary vane type, for developing hydraulic pressure. A coupling 197 connects the pump shaft with the drive shaft of a motor 198 mounted upon a bracket 199. A filler tube 200 is provided for the tank 194. The outlet pipe 201 from the pump 196 is connected with an accumulator and relief valve 202, the tube 205 conveying the oil under pressure to the several fluid operated components. The relief valve 202 is provided with a relief vent tube 204. The return circuits or tubes of the hydraulic system are connected with a pipe 203 whereby the oil is returned from the various components to the tank 194.

The vertically movable head or carriage 64 is provided with means for intermittently feeding the grinding wheel downwardly into contact with a wheel dressing means 320 with each reciprocation of the ram 40. The construction of head and feeding means therefor are illustrated in detail in FIGURES 5 through 10, the feeding mechanism being utilized with an abrading grinding wheel. The head 60 is equipped with a portion 208 the latter having a central bore receiving a tenon 212 formed on a threaded shaft 214.

The shaft 214 is formed with a collar 216 seated in a recess to maintain the shaft against movement in an upward direction. Secured to the upper end of the tenon 212 is a fitting 218 provided with a polygonally shaped portion 220 adapted to accommodate a crank or other tool for manually rotating the threaded shaft 214. The member 208 is formed with a projection 221 provided with bosses 222 adapted to accommodate a clamping screw 223 to lock the shaft 214 to the member 208.

The member 60 is provided with a boss portion 226, shown in FIGURE 9, within which is journaled a shaft 228. Formed on the shaft 228 is a worm 230 which is enmeshed with a worm wheel 232 which is formed as an integral part of a sleeve member 234 shown in FIGURE 8. An axial bore in the member 234 is threaded for enmeshment with the threaded shaft 214. The member 234, in effect, provides a nut which, when rotated, elevates or lowers the portion 208 and the head 64 upon which is journaled the shaft 69 carrying the grinding wheel 72.

The nut 234 is held in a recess formed in the portion 69 by a retaining sleeve 235 secured in position by screws 236, as shown in FIGURE 8. The shaft 228 is provided with a tenon 238 which extends into an enclosure 239 secured to the member 60. Keyed to the shaft portion or tenon 238 is a sleeve 240 which forms a component of two "one-way" clutches or overrunning clutch mechanisms.

As shown in FIGURES 5 and 8, the sleeve 240 is formed with two sets of pockets 242 and 244. Disposed in the pockets 242 are cylindrically-shaped clutch members 246 and disposed in the pockets or recesses 244 are cylindrically-shaped clutch members 248. Surrounding the sleeve 240 at the region of the clutch members 248 is a hardened bushing 250 which is engaged by the clutch rollers or members 246. Surrounding the portion of the sleeve 240 adjacent the clutch members 246 is a gear 252. The interior surface of the gear is adapted for cooperation with the clutch members or rollers 246 as shown in FIGURES 5 and 8.

Means is provided for biasing the clutch members 246 into clutching or wedging engagement between the interior surface of the gear 252 and the flat surfaces of the sleeve 240 defining the recess or chamber 242 for the clutch members 246. The sleeve 240 is formed with bores accommodating plungers 254, as shown in FIGURE 5, which are biased by springs 256 to urge the clutch rollers 246 in wedging or clutching engagement with the sleeve 240 and the gear 252.

The clutch rollers or members 248 are provided with similar biasing plungers and springs carried in bores formed in the sleeve 240 but are arranged in opposite

angular relation to the angles of the biasing plungers 254 and springs 256 shown in FIGURE 5. The end of the housing 239 is closed by a cover plate or cap 241. Thus, the clutch means provided by the rollers 246 facilitates 5 rotative movement of the sleeve 240 and the tenon 238 on the shaft 228 when the gear 252 is moved in a counter-clockwise direction as viewed in FIGURE 5 actuated by means hereinafter described.

Rotation imparted to shaft 228 rotates the worm wheel 232 to impart a feeding motion to the screw or threaded shaft 214. The clutch means embodying the rollers 248 is effective to prevent rotation of the sleeve 240 and shaft 228 in the opposite direction when the gear 252 rotates in a reverse direction to that instituting a feeding motion of 15 the threaded shaft 214. The means for actuating the gear 252 is illustrated in FIGURES 5 through 8.

The housing 239 is formed with a cylindrically shaped portion 260 which is bored to accommodate a slidably movable member 262, a longitudinal surface region of 20 which is formed with rack teeth 264, the rack teeth being in mesh with the teeth of gear 252. Secured to one end of the cylindrically shaped portion 260 is a sleeve 266 having a recess accommodating an expansive coil spring 268, one end of the spring bearing against an end of the 25 rack member 262.

Secured to the rack member by a pin 269 is a rod 270 which is connected by means of a pin with a cylindrically shaped rotatable member 272. The cylindrically shaped member 272 is provided with graduations 273 which 30 cooperate with an index at the end of a member 275. The interior of the cylinder 272 is threaded to accommodate a threaded portion 276 of the member 275 integral with the rod 270.

Rotation of the cylinder 272 effects a longitudinal 35 movement to the rod 270 and the rack 262 for the purpose of adjusting the relative position of the rack member 262 to vary the extent of rotative movement of the gear 252 with each reciprocation of the slide rack member 262. The rack member 262 is formed with a tenon or extension 40 280 which projects through an opening in a cover member 282 secured to the cylindrical portion 260. The shoulder 284 at the juncture of tenon 280 with the rack portion 262 limits the endwise movement of the rack in one direction.

Mounted upon an upper wall of the stationary housing 36 enclosing the ram 40 is a bracket 286. The bracket 286 is equipped with a pin 288 which provides a mounting for a member 290. The member 290 and the bracket 285 are provided with registering openings which accommodate a shear pin 292, which in cooperation with the pin 288 normally provides a fixed position for the member 290. The member 290 is formed with a boss portion 293 provided with a bore 294 in which is slidably mounted a plunger 295.

One end region of the boss portion 293 is formed with a slot 296. The plunger 295 is provided with an extension or rod portion 297, a transversely extending pin 298 being fitted in an opening in the rod portion 297 to limit endwise movement of the plunger 295 in a left-hand direction as viewed in FIGURE 5, the pin cooperating with the slot 296 to prevent relative rotation of the plunger 295. An expansive coil spring 299 is disposed in the bore 296, the spring 299 being comparatively strong so as to normally maintain the plunger 295 in the position illustrated in FIGURE 5.

As shown in FIGURES 5 and 7, an end of the plunger 295, exteriorly of the cylindrical member 293, is provided with a slot accommodating the end of an abutment member or bar 300. The abutment or bar is pivotally connected with the plunger 295 by a headed stub shaft 301 secured to the bar 300 by a pin 302. The abutment or bar 300 is fashioned with a square shoulder portion 304 which engages the bottom surface 305 of the slot in the plunger 295 providing a stop means for normally

maintaining the bar 300 in alignment with the portion 280 of the rack member 262.

The end of the bar 300 is adapted to be engaged by the end surface 281 of the extension 280. The pivotal mounting for the abutment or bar 300 on the stub shaft 301 provides means whereby the abutment bar 300 may be swung upwardly and out of the path of reciprocation of the rack member 262 and its extension 280.

With particular reference to FIGURES 5 and 8, the portion 60 is provided with sockets or wells 306 which accommodate coil springs 307, the springs extending into bores 308 provided in the portion 208.

The upper portions of the bores 308 are threaded to accommodate the threaded heads 309 formed on the upper ends of rods 310 which extend downwardly in the interior of the coil springs 307. The springs 307 serve to maintain pressure or bias on the member 208 with respect to the member 60 so as to prevent any lost motion between the threads 214 and the nut 234. The springs are of substantial length in order to accommodate the feed movements of member 208 with respect to the member 60.

As shown in FIGURE 9, the portion 60 is provided with a tang 312 carried in ways 314 whereby the head construction 64 moves in a vertical direction effective by successive strokes of the feeding means. When the grinding machine is used with an abrasive grinding wheel, it is necessary to dress the wheel at each reciprocation of the ram and grinding stroke of the grinding wheel. As shown in FIGURE 1, a bracket 317 is secured to a member 318. The forward portion of the bracket 317 supports a holder 319 in which is mounted the dressing diamond or dressing tool 320.

The dressing tool may be adjustably supported in order to accommodate grinding wheels of different diameters. The cam means for controlling the path of movement of the abrasive grinding wheel during reciprocation will be hereinafter described. The grinding wheel feeding means particularly shown in FIGURES 5 through 10 is for the purpose of feeding the head 64 and the grinding wheel 72 downwardly in infinitesimally small increments so as to effect an engagement of the periphery of the abrasive grinding wheel with the dressing tool 320 at each grinding cycle or stroke of the grinding wheel reciprocated by the ram 40.

The operation of the feeding means shown in FIGURES 5 through 10 is as follows: A crank or other tool (not shown) is applied to the polygonally shaped portion 220 of the fitting 218, the rod 212 and the threaded shaft portion 214 rotated in a direction to adjust the head 208, the plate or head 62 and the grinding wheel 72 in a vertical direction until the periphery of the grinding wheel 72 is in a position to engage the tip of the dressing diamond 320 during a reciprocatory movement of the grinding wheel 72 and the ram 40.

The extent of the automatic downward movement of the head 64 and the grinding wheel 72 with each stroke of the ram 40 is adjusted by rotating the member 274, shown in FIGURE 5, which, through the medium of the threads 276, adjusts or establishes the position of the plunger 280 with respect to the abutment 300 carried by the member 290 supported by the stationary bracket 286. The spring 268, which is comparatively weak, is adapted to take up any lost motion in the engagement of member 274 with the threads of member 276.

The indicia on the tapered portion 273 cooperates with the index on portion 275 of the threaded member 276 to indicate the relative position or setting of the plunger 280. When the ram 40, the head 64 and the components carried by the head shown in FIGURE 5 are moved through a retractive stroke, that is, in a right-hand direction as viewed in FIGURES 1 and 5, the end of the plunger 280 strikes the abutment 300 which is held in a static position under the influence of the comparatively strong spring 299 so that the abutment 300 is relatively stationary.

The engagement of the plunger 280 with the abutment 300 stops or interrupts the retractive movement of the plunger 280 carried by the member 260, the latter continuing its movement in a right-hand direction as determined by the extent of movement of the ram 40 in a right-hand direction, this movement being determined by the extent of movement of the piston 98 in the cylinder 93 shown in FIGURE 1. As the movement of the plunger 280 is thus arrested, the further movement of member 260 effects a slight rotation of the gear 252 as the teeth thereof are in mesh with the rack teeth 264 on the portion 262 of the plunger 280.

Through the medium of the clutch rollers 246, the rotation of the gear 252 in a counterclockwise direction effects slight rotation of the shaft 228 and the worm 230 to cause slight rotation of the worm gear 232.

As the gear 232 forms an integral portion of the nut 234, the threaded shaft 214 is moved lengthwise an infinitesimally small distance, lowering the portion 208, the head 64 and the bearings supporting the grinding wheel 72. In this manner, the grinding wheel is lowered to the extent of longitudinal movement of the screw 214.

On a forward or grinding stroke of the ram 40 and the grinding wheel 72 in a left-hand direction as viewed in FIGURES 1 and 2, the clutch rollers 248, acting in a direction opposite to the clutch rollers 246, provide a holding means for preventing reverse movement of the sleeve 240, the gear 252, and the shaft 228 preventing any relative vertical movement of the shaft 214 and the head carrying the grinding wheel.

Through the speed reduction provided by the worm 230 and the worm wheel 232, the grinding wheel may be dressed to the extent of only a few hundred thousandths of an inch per each grinding stroke, the extent of the feed movement downwardly of the grinding wheel being adjustable by varying the position of the adjusting means 274 shown in FIGURE 5.

A down feeding movement of the head 64 which journally supports the grinding wheel is as follows: During 40 retractive movement of the ram 40 and grinding wheel, the bar 262 is moved in a right-hand direction as viewed in FIGURE 5 until the end portion 280 engages the abutment block 300. During this portion of movement of the ram, no rotation is imparted to the gear 252 in mesh with the toothed rack portion 264 of member 262. As 45 the head 64 continues its retractive movement, the bar 262, remaining stationary due to its engagement with the abutment, effects rotation of the gear 252 and a down feeding of the head 64.

The down feeding action continues until the right-hand end of member 262 engages the abutment provided by member 266. Continued movement of the head 64 in a retractive direction merely compresses the spring 294 contained in the housing 293 during which time the wheel moves over the dressing diamond without further relative rotation of the gear 262 or downward movement of the head 64.

In the event the jamming is severe and the movement of the plunger 280 fully compresses the spring 294, stress will be placed upon the shear pin 292, shearing the latter and permitting the bracket 290 to pivot about its support 288 thus avoiding any damage to the mechanism other than the shearing of the pin 292.

The apparatus includes cam means for guiding the path of an abrasive type grinding wheel during its reciprocation by the ram to establish cutting strokes or abrading strokes of the grinding wheel in engaging the cutter being round and to dress the wheel by engaging the same with the diamond 320 during each stroke or reciprocation of the grinding wheel. One form of cam means usable 65 with an abrasive grinding wheel is illustrated in FIGURES 1, 13 and 31.

The cam 322 is supported upon a hardened plate 323 carried by a member or block 324, the latter being 70 cured to the mounting plate 14 shown in FIGURE 1

the cam being held in place by a screw 325. The ram 40 is provided with a bracket or block 326 provided with a hardened cam follower 327 which cooperates with the cam 322. The cam 322 is formed with angularly arranged surfaces 329 and 330 of an angularity to guide the grinding wheel 72 into proper engagement with the cutting faces 331 and 332 of the cutter C shown in FIGURE 31.

The cam 322 is provided with a second set of angularly arranged cam surfaces 333 and 334 for guiding the grinding wheel into engagement with the wheel dressing diamond or dressing tool 320 during reciprocation of the ram 40. The cam 322 is maintained in a stationary position when the arrangement shown in FIGURES 1 and 31 is utilized with an abrasive type grinding wheel 72.

The apparatus of the invention is adapted to be utilized as hereinafter described for electric or electrolytic disintegration of metal of a cutter and for such use, a novel cam construction is provided which is shiftable or relatively movable for purposes hereinafter explained.

The shiftable cam construction and supporting means employed with the apparatus shown in FIGURE 19 is illustrated in FIGURES 15 and 16. In this form the cam 340 and associated components are supported by member or block 335 similar in shape to the block 324 shown in FIGURES 1 and 31. The cam 340 and its supporting means are adapted for limited longitudinal reciprocation with each reciprocation of the grinding wheel 72 for a purpose to be hereinafter described.

As shown in FIGURE 15, the cam 340 is mounted in a T-shaped supporting member or cradle 342 formed with upwardly extending portions 344 engaging the ends 345 of the cam 340 to position the cam lengthwise of the member 342.

The stem 346 of the member 342 extends into a recess 348, the width of the recess being greater than the width of the stem portion 346 in order to provide for limited longitudinal movement of the member 342 and the cam 340. The cam support or carrier 342 is guided for longitudinal movement by means of side plates 350 secured to the member 335 by suitable screws 352. The cam 340 is held in place by a screw 341.

The member 335 is formed with lengthwise arranged aligned bores 354 and 355. The bore 354 accommodates a piston or plunger 356 and the bore 355 accommodates a similar piston or plunger 357. The ends of the bores are closed by plates 358 and 359. The outer end region of each of the plungers 356 and 357 is provided with a reduced tenon portion 360 providing a space to accommodate a fluid such as oil under pressure for effecting longitudinal movement of the pistons.

It should be noted that the inner ends of the pistons 356 and 357 are in abutting relation with the side surfaces of the portion 346 of the cam or template carrier 342. Each of the pistons 356 and 357 is provided with a recess accommodating a sealing ring 362. The member 335 is formed with a channel 364 in communication with a transverse fore or channel 365, a fitting 366 provided in the member 335 in communication with the channel 365 is connected with a tube 367 for conveying fluid such as oil under pressure into and away from the chamber at the end of the piston 356.

The member 335 is provided with a channel or duct 368 which is in communication with a transverse channel or duct 369 which is in communication with a fitting 370 connected with a tube 371 for conveying oil into and out of the chamber at the left-hand end of the piston 357 as viewed in FIGURE 15. Valve means, herein-after described, is arranged to control the flow of oil into and out of the chambers adjacent the ends of the pistons 356 and 357 to effect reciprocation of the template or cam carrier 342 with each reciprocation of the ram 40 and the grinding wheel carried thereby.

The template or cam member 340 has its upper surface configurated or shaped to guide a rotatable electrode wheel

585, shown in FIGURE 19 adjacent the teeth of the cutter being processed by electric disintegration so as to impart a desired contour to the teeth of the cutter. In order to impart vertical motion to the electrode wheel 585 during its reciprocation, the cam follower or template follower means 327 engages the cam 340 in the same manner that the follower 327 engages the cam 322 shown in FIGURES 1 and 13.

The follower 327 being in direct engagement with the cam or template contour of the upper surface of the cam 340 is controlled by the cam surfaces to impart movement to the ram 40 and the electrode wheel 585 and component parts carried thereby about the axis of the pivot shaft 34 so as to effect vertical movements of the electrode wheel to apply the desired contour by electric disintegration to the teeth of the cutter being ground.

Multitoothed rotary cutters have teeth of different shapes and each cutter requires a particular contour of cam in order to properly grind or shape the teeth. The 20 cams are therefore readily removable to facilitate changing cams. The apparatus includes fluid pressure actuated means for elevating the ram 40 and components carried thereby and holding the ram in elevated position to facilitate the removal and replacement of a cam from the cam carrier.

One arrangement for accomplishing this purpose is illustrated in FIGURES 1 and 11 through 14. As shown in FIGURE 14, a rectangular tubular portion 37 of the stationary ram carrier 36 forms an enclosure and guide means or ways for the ram 40. The ram carrier 36 is provided with a transversely extending web portion 376 provided with an opening to accommodate a comparatively short cylinder 378.

The cylinder 378 is provided with a flange portion 380 which is secured to the web 376 by means of screws. The upper end of the cylinder is provided with a head or closure 382. Reciprocably disposed in the cylinder is a piston 384 which is provided with a sealing ring 385 to prevent leakage of oil or other fluid along the piston. 40 Mounted upon the plate 14 is a block or fluid distributor 388.

The distribution block 388 is formed with a passage 390 connected with an oil pressure supply line or pipe 391. The block 388 is provided with a passage 392 which 45 is connected with a waste or fluid return line 393 which is connected with the fluid return pipe 203, shown in FIGURE 1 on the reservoir 194. A passage 395 is in communication with the passage 390 and a valve means 396, the valve being manually operated by a finger grip 50 member 397.

The passage 392 is in communication with a tube 399 connected with a T-shaped fitting 400 which is in communication with the valve means 396 by tubes 401 and an L-shaped fitting 402, as shown in FIGURES 11 and 55 12. As shown in FIGURE 12, a sleeve 403 is disposed in the tube 399 and is fashioned with a restricted passage 404 to facilitate restricted flow of fluid under pressure in the T-shaped fitting 400 into the waste or return line 393.

60 A branch of the T-shaped fitting 400 is connected by means of a tube 406 with a passage in the cylinder head 382 to accommodate flow of fluid under pressure into the cylinder 378 to depress the piston 384. The operation of the ram elevating means is as follows: The manually operable valve 397 is normally maintained closed so that normally there is no fluid pressure in the tube 406 or above the piston 384. In order to depress the piston to engage the same with a portion 408 carried by the plate 14, the operator manipulates the valve 397 to admit fluid under pressure from the line or pipe 391 through pipes 401, T-shaped fitting 400 and pipe 406 into the upper end of the cylinder 378.

Under the pressure of the fluid admitted into the cylinder, the piston 384 is forced downwardly as viewed in

FIGURES 1, 13 and 14, engaging the piston with the upper surface of an extension 408 of block 324 or extension 408' of block 335 where the latter is employed. Downward movement of the piston rocks the ram carrier 36, the ram 40, the grinding wheel and other components associated therewith about the shaft 34 to elevate the cam follower 327 above and out of contact with the cam so as to facilitate access to the cam block carrier 323 shown in FIGURE 1, or the cam block carrier 342 shown in FIGURES 15 and 19 to remove and replace the cam.

It should be noted that the restricted passage 404 permits a small amount of fluid under pressure in the T-shaped fitting 400 to flow into the return line 393 but the area of the restriction 404 is substantially smaller than the area of fluid passage through the valve means 396. Thus while some fluid under pressure passes through the restriction 404, sufficient flow of fluid is established into the cylinder 378 to slowly depress the piston and elevate the ram carrier 36, the fluid pressure being maintained in the supply line while the cam is being removed and replaced by another cam.

After the interchange of cams has been effected, the operator closes the manually operated valve 397, interrupting the supply of fluid under pressure to the cylinder 378.

With the pressure fluid supply interrupted, the pressure on the piston 384 is relieved by flow of spent oil through the metering restriction 404 into the waste or return line 393 so that the weight of the ram carrier 36 causes the same to swing in a counterclockwise direction as viewed in FIGURES 1 and 19 to again reestablish contact of the cam follower 327 with the cam as the piston 384 is moved upwardly in the cylinder under the downwardly acting weight of the ram carrier and parts or components associated therewith. Through this arrangement, movement of the ram carrier about the shaft 34 is effected through the manipulation of a single valve member 397.

FIGURES 20 through 23 illustrate a novel automatic lubricating means for lubricating the surfaces of the slideable ram 40 and its support. The lubricating arrangement for the ram is associated with a hydraulic indexing valve which is illustrated in FIGURE 23. As shown in FIGURE 22, the ram 40 is arranged for slideable movement between parallel surfaces of portions 450 of the ram carrier 36 the lower surface 452 of a housing 453 and surfaces 454 of member 36.

The ram 40 is provided with a block or abutment 455 which is movable with the ram and is engageable with a plunger 456 formed with an enlarged cylindrically shaped valve portion 458 shown in FIGURE 21. A coil spring 460 is contained in the bore 461, a closure plug 462 being threaded into the entrance of the bore and forming an abutment for the spring 460. The spring 460 normally biases the plunger 462 and valve portion 458 in a left-hand direction as viewed in FIGURE 21.

As shown in FIGURE 22, the central region 464 of housing 453 is formed with a bore 466 accommodating a cylindrically shaped rotatable drum or member 470, a peripheral region of the drum 470 being formed with ratchet teeth 472. The housing 453 is provided with vertically arranged transversely spaced bores 474 and 475. Disposed within the bore 474 is a cylindrically shaped bar or rod 476.

Disposed in the lower portion of the bore 475 is a stationary rod 478 and above the rod is a relatively movable plunger or rod 480. The rod 476 in the bore 474 is provided with a recess accommodating a spring plate or pawl 483 secured to the rod 476 by rivets 484, the pawl 483 engaging the teeth 472 of the drum 470. The rod 480, which is slideable in the bore 475, is formed with a recess in which is disposed a spring plate or pawl 485 secured to the rod by rivets 486, the pawl being adapted for engagement with the teeth 472 on the drum 470.

The slideable rod 480 is biased in one direction under

the influence of an expansive coil spring 488 which abuts against a cover member 490 secured to the housing portion 453. It will be apparent from FIGURE 22 that reciprocable or slideable movements of rod 480 will effect intermittent rotation of the drum 470 and the holding pawl 483 assures rotation of the drum in only one direction, viz., counterclockwise as viewed in FIGURE 22.

The lubricating means illustrated in FIGURES 20 through 22 and 23 is associated with slideable valve means shown in FIGURE 4 which controls the hydraulic indexing of the cutter or work holder 130 shown in FIGURE 1 for moving the cutter to bring successive teeth into position to be ground sharpened. As shown in FIGURE 4, the channel 566 is in communication with the lubricating mechanism shown in FIGURES 20 through 23 by a passage 533 in the housing 92 containing the piston 98 shown in FIGURE 1.

The indexing valve member 500 is arranged to be reciprocated by fluid under pressure, as for example oil. Secured to the housing 92 is a manifold member 502 provided with fluid conveying channels 504, 505, 506 and 507. These fluid conveying channels are in communication with the interior of the sleeve 499 through suitable ports shown in FIGURE 3. One end of the bore 498 accommodates a plug or sleeve 503 provided with a fluid passage 510 in communication with a fluid channel 511 which is in communication with a channel 512 shown in FIGURE 22.

The valve member 500 is formed with enlarged cylindrical portions 514, 515 and 516 which are connected by portions of reduced diameter, one portion 517 extending beyond the enlarged portion 514. The valve member 500 is slideable in the interior of the sleeve 499 and serves to control fluid flow to control the cutter indexing mechanism. The channel 504 is connected with a supply of oil under pressure supplied to the region within the sleeve 499 between the portions 514 and 515 of the valve member.

The channel 504 is adapted, when the valve member 500 is shifted, to move the portion 514 beyond the channel 504 to convey oil from the supply channel 505 into the channel 504 to operate the indexing mechanism 190 shown in FIGURE 1. During this movement of the valve, the portion 515 blocks the channel 506 which conveys fluid to the indexing return mechanism 188 to rotate the work support 130 for a slight distance to bring a tooth of the cutter in engagement with the lip rest 355 shown in FIGURE 1.

When the valve member 500 is moved in the opposite direction, the fluid channel 506 for the index return means 188 is placed in communication with the waste channel 520, the waste oil being returned to the reservoir 194 shown in FIGURE 1. Oil under pressure is admitted through channels 510 and 511 from the recess 528 in plunger 458 shown in FIGURE 21 for actuating valve member 500 to a work holder indexing position.

The fluid pressure in channel 510 acts against the outer end surface of the enlarged portion 516 on the valve member 500 to move the same upwardly to initiate an indexing operation by flow of oil through the valve chamber from channel 505 to channel 504. The valve member 500 is formed with a longitudinally central channel 522 having an entrance 523 into the space between the enlarged members 514 and 516 of the valve member 500.

When flow pressure is removed from the lower surface of the enlarged portion 516, the oil under pressure from the supply channel 505 flows through the entrance port 523 and channel 522 into the region or space 524 at the end of the portion 517 and the oil pressure in the chamber 524 forces the valve member 500 downwardly to the position shown in FIGURE 3, to establish communication between the oil pressure supply channel 505 and the index return channel 506 and to connect the indexing channel 504 with the waste channel 519 to facilitate the return flow of oil in the indexing channel to the reservoir 194.

The housing member 453 is provided with channels for conveying oil under pressure to the arrangement for establishing intermittent lubrication to the ram surfaces. The

channel 512 shown in FIGURE 20 is in communication with a channel 526 shown in FIGURE 21 which is in communication with the bore 461 accommodating the plunger 458. The plunger 458 is formed with a peripheral recess 528 which is in communication with a central channel 530 in a portion of the plunger 458 so that when the plunger is moved in a right-hand direction as viewed in FIGURE 21, the peripheral recess 528 establishes communication of the fluid channel 526 with the peripheral recess 528, the central channel 530 in the plunger and the bore 461.

The bore 461 is in communication with channels 532 and 533 shown in FIGURES 20 and 22 with a valve means 563 shown in FIGURE 4 which valve means is arranged for intermittent movement to intermittently establish oil pressure in the channels 532 and 533. The valve means 563 is of the spool type and is oscillated by reciprocation of the ram.

The oil channel 532 is in communication with the bore 475 containing the reciprocable rod 480 by a channel 535 shown in FIGURE 22. Thus, when oil pressure is built-up in these channels under the influence of a particular position of the valve 563, the plunger 480 is moved forwardly as viewed in FIGURE 22 and, as the pawl 485 is arranged to engage the teeth on the drum 470, the drum is moved through a distance of one tooth, there being preferably a large number of teeth, for example, one hundred teeth formed on the drum.

The pawl 483, engaging the teeth on the drum 470, holds the drum against retractive movement as the plunger 480 is moved downwardly under the pressure of spring 488 when the oil pressure is relieved in the channels 435, 432 and 433 upon movement of the spool valve 534.

Thus, the drum 470, if fashioned with one hundred teeth, will be rotated one complete revolution for each one hundred complete reciprocations or cycles of the ram 40.

The drum 470 is provided at its central axis with a short bore 538 which communicates with a radial channel 539 formed in the drum. The channel 539 is adapted to register with a channel 540 formed in the housing 453 once during each revolution of the drum, the channel 540 being in communication with the bore 461. Secured to the housing 464 is a casing 541 formed with a chamber 542 accommodating a lubricant metering fitting 543 having communication with the bore 538.

The lubricant fitting 543 is of a metering valve type of conventional construction which is adjusted or adapted to deliver a few drops of oil or lubricant into the chamber 542 during each revolution of the drum 470. The casing 541 is formed with diverging channels 545 and the adjacent region of the housing 453 is provided with channels 546 registering with channels 545 for conveying the metered oil from the chamber 542 onto the upper bearing surfaces of the ram 40. The frontal portion of the casing 541 is equipped with a closure plate bearing a sight window 548 for visual inspection.

The control for effecting reciprocation of the ram 40 by fluid under pressure directed against the piston 98 shown in FIGURE 1 is illustrated in FIGURE 4. The master control valve 102 manipulated by the handle 104 initiates the operation of the machine by releasing fluid under pressure to the arrangement shown in FIGURE 4 for reciprocating the piston 98 to reciprocate the ram 40.

As shown in FIGURE 4, a valve supporting member 92 is provided with a longitudinal bore 554, the axis of which is arranged parallel with the axis of travel of the ram 40. Mounted within the bore 554 is a slide valve member 550 which is reciprocated in the bore 554 by oil under pressure admitted alternately into opposite end regions of the bore 554.

Mounted upon the member 92 is a plate 553 which is provided with a transverse bore accommodating a rotatable shaft 569. The member 92 is provided with a cylindrical sleeve 561 which is provided with openings 562 shown in FIGURE 4. Provided on the shaft 560 and

rotatable within the sleeve 561 is a valve portion or head 563. The valve portion 563 is formed with fluid passages arranged to alternately register with a fluid supply tube 503 from the chamber containing the master control valve 102 and fluid passages 565 and 566 for establishing fluid pressure alternately to the passages and to the waste line 567 to reciprocate the valve 550. The valve portion 563 is formed with an opening which registers with a fluid passage 568 formed in member 552.

- 10 Disposed longitudinally of the ram and reciprocable therewith is an operating rod 576 shown in FIGURES 2 and 4 having its forward end connected with the plate 62 so as to be reciprocated on an axis parallel with the axis of the ram. The rear portion of the rod extends through 15 a boss portion (not shown) formed on the plate 42 at the rear of the ram to provide suitable guide means for the rod. Mounted upon the rod are abutments 572 and 574 which are adapted to engage a member 576 which is keyed or otherwise secured on the shaft 560.
- 15 The alternate engagement of the abutments 572 and 574 with member 576 causes partial rotation of the shaft 560 and the valve portion 563 in alternate directions. The fluid channel 565 is in communication with one end of the bore 554 by a channel 578, and the channel 566 20 is in communication with the opposite end of the bore through a channel 579. At the time of engagement of an abutment 572 or 574 with the member 576, the valve head or portion 563 is moved to a position to admit oil under pressure to flow alternately into the ends of the bore and 25 effect reciprocable movements of the valve 556.
- 20 The enlarged portions of the reciprocable valve 556 cooperate with ports (not shown) for controlling the flow of oil under pressure alternately into opposite ends of the cylinder 93 to direct the piston 98 in alternate directions 30 for reciprocating the ram 40.

- 30 The modification shown in FIGURE 19 adapts the apparatus for use in removing metal of a cutter by electric energy through electrolytic action. In the electrical disintegration or electrolytic method of dressing or shaping 40 a cutter by the use of the arrangement shown in FIGURE 19, it is essential that the arrangement for driving or 45 rotating an electrode wheel 585 be insulatingly supported from the adjacent structure of the apparatus as the electrode wheel driving means conducts current to the wheel 45 for metal disintegrating purposes.

- 45 The wheel or moving electrode 585, employed in lieu of an abrasive wheel, is preferably fashioned of powdered current conducting metal and diamond particles or particles of mineral material sintered together or other types 50 of current conducting wheel may be employed. The electric system for removing metal from the cutter does not cause any appreciable wear of the rotating electrode wheel 585 as the wheel does not have direct contact with the cutter teeth or work piece. The system embraces the 55 use of an electrolyte which is continuously delivered onto the wheel in a manner whereby the electrolyte is always present at the region of the wheel 585 adjacent the cutter tooth being processed.

- 55 As the periphery of the wheel 585 is not in actual contact with a cutter tooth, no appreciable heat is developed. The electrolyte bridges the small gap between the electrode wheel and the cutter tooth and is effective in conducting current for disintegrating the metal of the cutter teeth. It is believed that in the electric metal removing or disintegrating process, the surface of the cutter tooth adjacent the electrode wheel is oxidized by the action of the current and in this fashion the cutter is contoured or sharpened as the metal oxide film is brushed away by the diamond particles in the wheel.

- 70 The electrolyte preferably consists of water fortified with a suitable current conducting salt, such as sodium acetate, sodium citrate, sodium titrate, or other salt. A stream of the electrolyte is delivered by a tube (not shown) onto the periphery of the wheel 585 at a region

in advance of that area of the wheel in close proximity to the cutter tooth being processed.

A fluid pump 820 of conventional character is utilized to deliver the stream of electrolyte through a tube 822 onto the wheel to assure an adequate continuous film of the electrolyte on the periphery of the wheel 585. It should be noted that the periphery or operative face of the wheel 585 comprises two angularly arranged peripheral surfaces 596 and 598, each surface being arranged to perform an individual metal disintegrating stroke when the wheel is moved by the ram 40' into close proximity with a cutter tooth.

In the arrangement shown in FIGURE 19, the adjustable head carrying the grinding wheel and the feeding means therefor shown in FIGURE 1, is removed from the apparatus and the plate 587 which carries the housing 588 is directly secured to the end of the reciprocating ram 40' by means of screws (not shown). An apron or curtain 584 of rubber may be provided as shown in FIGURE 19 to prevent contact of the electrolyte with the frame structure supporting the ram and associated components.

Secured to the plate 587 is an annular disc 590 formed of nonmetallic insulating material secured to the plate 587 by means of screws 592. Disposed within the interior of the annulus 590 is a tubular member 600 provided with a flanged portion 594 which is secured to the insulating member 590, the tubular member 600 extending a substantial distance into the hollow ram 40'. The end regions of the tubular member 600 accommodate anti-friction or ball bearings 602 and 603 which journally support a shaft or spindle 605.

The forward end of the spindle 605 is provided with a tapered portion 606 upon which is secured a hub 607 supporting the electrode wheel 585. The hub 607 is secured in position by a nut 608 threaded onto a tenon on the end of the shaft 605. Formed on the opposite end of the shaft 605 is a threaded portion 610 from which projects a tenon 611, the latter extending into a bore formed in an end of a drive shaft 612.

A bushing 614 abuts against the inner race of the bearing means 603 to properly position the spindle 605 within the tubular member 600. The bushing is carried by the threaded portion 610 of the spindle and is held in locked position by setscrews (not shown). An annular cap 616 is secured to the end of the tubular member 600 and is equipped with a sealing ring to prevent the ingress of foreign matter into the bearing supporting the spindle 605.

Disposed at the rear end of the ram 40' is a hollow housing 620, a wall 621 thereof being secured to the ram by screws 622. An upwardly extending portion or lug 623 on the housing provides an anchor for the piston rod 97' connected with a piston 685 disposed in the cylinder 92' which is subjected to hydraulic pressure for reciprocating the ram 40'. The housing 620 is provided with an upwardly extending web portion 625 formed with a platform 626 which supports the motor 46' for driving the electrode wheel 585.

Secured to the rear of housing 620 is a member 628, the member 628 having a tubular portion 630 in which is mounted a sleeve 631. The sleeve 631 is provided with counterbores in each end region to accommodate anti-friction or ball bearings 633 and 634 in which is journaled a shaft or spindle 635. The outer end of the shaft supports a sheave wheel (not shown) which is identical with the sheave wheel 52 shown in FIGURE 1 and which is driven by a belt engaging a driving sheave or pulley mounted upon the shaft of the motor 46'.

The sleeve 631 is formed of nonmetallic insulating material to insulate the spindle from the housing. The region of the shaft 635 within the housing 620 is formed with a tapered portion 637 upon which is mounted a copper ring 639 held in place by a nut 640 mounted on a

threaded tenon portion on the shaft 635. Extending axially from the threaded portion accommodating the nut 640 is a projection or tenon 642, the adjacent end region of the drive shaft 612 being split lengthwise for a short distance at the region of the tenon 612.

Clamping bolts 644 extend through transverse openings in the split portions of the shaft to draw the split portions into close engagement with the extension 642 to provide intimate metallic contact between the shaft 612 and the tenon 642 to facilitate the conduction of electric current from the current conducting ring 639 to the drive or connecting shaft 612.

The opposite end of the shaft 612 accommodating the projection or tenon 611 on the spindle 605 is also split and the furcations drawn into intimate metallic contact with the projection 611 by bolts 646 to provide a current conducting coupling between the drive shaft 612 and the spindle 605.

The plate 628 secured to the housing 620 is provided with projections 648, one of which is shown in FIGURE 19, supporting a brush holder 650 connected with a terminal 652 connected with a source of low voltage, high amperage current. The holder 650 is provided with brushes (not shown) engaging the periphery of the ring 639 to convey current from the terminal member 652 to the ring. The brush holder is supported upon an insulating plate 654, the insulating means being supported by the projections 648.

A trough-like member 656, a portion of which is shown in FIGURE 19, is adapted to collect the electrolyte as it flows down over the cutter or work piece C mounted upon the indexing shaft 130. Means is provided for establishing a current conducting connection with the work piece carrying member or shaft 130. As shown in FIGURES 1 and 19 the housing 124 enclosing the cutter support 130 is provided with a fitting 158 supporting a member equipped with brushes 159 engaging a bronze sleeve on the periphery of the portion 131 of the cutter support 130, the brushes being preferably spring biased into contact with the portion 131.

A current conducting cable 161 secured to the member 158 completes a circuit for the current delivered to the metal disintegrating electrode wheel 585 through the wheel driving shaft construction hereinbefore described.

The shiftable cam supporting arrangement illustrated in FIGURES 15 and 16 is adapted for controlling the path of movement of the metal disintegrating electrode wheel 585 in grinding the faces of the teeth of a cutter. The shiftable or movable cam arrangement makes possible the electrical disintegration of metal on one face or surface of a cutter tooth when the ram moves in a forward direction and a metal disintegrating stroke of the wheel upon movement of the ram in the opposite direction to contour or shape the other face or surface of a cutter tooth.

The shifting cam arrangement shown in FIGURES 15 and 16 makes possible the accurate contouring of the radius or curvature at the apex of two cutting edges of a cutting tooth as a portion of such radius is contoured by movement of the wheel 585 in one direction and the remaining portion of the radius or curvature formed during movement of the wheel in the opposite direction under the influence of reciprocation of the ram 40.

As hereinafter described, a fluid actuated arrangement for reciprocating the ram effects traverse of the metal disintegrating wheel or electrode 585 at a comparatively slow speed during the metal disintegrating periods of its cycle and to be traversed at comparatively rapid speeds in its idle periods of traverse.

FIGURE 32 is illustrative of the path or locus of traverse of the disintegrating wheel or electrode 585 under the influence of the cam shown in FIGURE 15 exemplifying the metal disintegrating and idle movements in a complete cycle of reciprocation of the ram 40' in re-

moving metal from two angular faces of a cutter tooth. Considering the diagram of FIGURE 32 in connection with the contour of the cam illustrated in FIGURE 15 and the cutter tooth of FIGURE 33, the flat portion 670 on the cam provides for guide traverse of the electrode wheel 585 through the distance identified at 670' in FIGURE 32.

The angular facet 672 on cam 340 controls the path of traverse of the wheel through the horizontal distance indicated at 672'. The region 672' is effective to grind one face 672" shown in FIGURE 33 of the cutter tooth. The ram moves at a comparatively slow rate through the metal removing stroke represented by the distance indicated at 672'. The wheel 585, at the end region of this metal removing stroke, grinds one-half of the radius on the apex of the cutter tooth at the region indicated at 674' on FIGURE 32, which represents the high point of the cam shown in FIGURE 15.

At the terminus or high point of the angular cam surface 672, a flat area 676 is fashioned on the cam 340 of a dimension lengthwise of the cam sufficient to carry or guide the wheel 585 beyond the end of the face 672" of a tooth of the cutter C by the cam follower 327' carried by the ram 40'.

The second angular guide surface 678 formed on the cam 340 is at a position such that the wheel 585 being moved further in a forward direction by the particular position of the cam 340 is guided by surface 678 in a path sufficiently spaced from the face 678" of the cutter tooth so that during this traverse of movement of the wheel represented by the distance 678' on FIGURE 32, no metal disintegrating or shaping of the cutter tooth results. During this idle period the ram is advanced at a comparatively fast rate during traverse of the wheel through the distance indicated by 678'.

The ram 40' has reached its maximum forward stroke at this point and the cam support 342 and the cam 340 are rapidly shifted or moved by hydraulic means in a manner hereinafter described. With particular reference to FIGURE 15, the cam 340 is shifted from its extreme left-hand position to a right-hand position, the cam moving through a distance equal to the difference in width of the tang portion 346 of the cam carrier 342 and the width of the slot 348 formed in the supporting member 335.

This shifting of the cam 340 influences the follower 327' to effect movement of the wheel 585 toward the cutter tooth so that the periphery of the wheel 585 is shifted to a position to effect a contouring, shaping or metal removing stroke over the cutter tooth surface 678". With particular reference to FIGURE 32, the cutting stroke effective on the tooth surface 678" takes place at the first portion of the movement of the ram 40' represented by the distance 678a.

During this period of movement of the ram, the hydraulically actuated means is controlled to effect a comparatively slow movement of the ram and wheel 585 to permit proper metal disintegrating action on the surface 678" of the cutter tooth. Due to the previous shift in the position of the cam 340 at the end of the forward stroke of the ram, the flat spot 676 guides the follower 327' out of effective metal disintegrating position so that as the follower moves in a right-hand direction along the cam surface 672, the periphery of the wheel 585 is spaced from the cutter surface 672" throughout the distance indicated at 672a.

During the traverse of the cam through the distance 672a and the distance 670a, the ram is moved at a comparatively high rate of speed as no operative metal removing action is taking place. When the ram has reached its maximum point of retraction, the cam 340 is moved by hydraulic means in a left-hand direction as viewed in FIGURE 15 preparatory to a cutting stroke on a succeeding tooth of the cutter which is indexed into operative position.

During initial forward movement of the cam 340 through the distance indicated at 670' on FIGURE 32, no metal removing action occurs, hence, the ram is moved at a comparatively high rate of traverse. In FIGURE 32, the periods of fast traverse are indicated by the letter F and the slow metal removing or operative strokes or periods indicated by the letter S. It will be seen from the diagram of FIGURE 32 that the ram moves through slow traverse only during the metal removing operations performed upon the faces 672" and 678" of a cutter tooth shown in FIGURE 33. Through this arrangement, the halves of the radius 680 at the apex of the surfaces of a cutter tooth are processed or shaped by the movements of the wheel 585 in opposite directions.

FIGURES 24 and 25 illustrate the piston and valve arrangement for actuating the ram at differential speeds to obtain ram traverse at comparatively fast and slow rates as the ram traverses the distances indicated schematically in FIGURE 32. The block or housing 92' shown in FIGURES 19 and 24 is formed with a bore 93' to accommodate a reciprocable piston 685 which is secured upon a reduced tenon portion 686 of the piston rod 97'.

The distal end of the piston rod is secured to the portion 623 of the housing 620 enclosing the brush holder unit shown in FIGURE 19. A bushing 687 surrounds the rod 97' and is formed with a stuffing gland 688 to prevent leakage of fluid along the piston rod. The opposite end of the bore 93' is closed by means of a cap 689.

The region of the block 92' at one side of the cylinder bore 93' is fashioned with a plurality of channels for conveying oil or other fluid into and away from the cylinder 93' and, in certain positions of the piston 685, to direct oil through a check valve system contained in the piston. A supply channel 690 conveys oil under pressure through channels 692 and 693 to a recess 695 formed in the bushing 687. The recess 695 is of substantial area in order to provide for adequate area adjacent the piston subject to fluid or oil pressure.

A channel 697 in the block 92' which, at times, is in registration with a peripheral recess or chamber 700 formed in the periphery of the piston 685 conveys oil away from the cylinder 93'. The block 92' is provided with a channel 702 equipped with a one-way check valve arrangement 725 of a character similar to that contained in the piston 685 shown in detail in FIGURE 25 for retarding movement of the piston during one of the metal removing strokes of the electrode wheel 585. The channel 697 is in communication with a channel 698.

The block 92' is formed with a channel 704 in communication with the cylinder 93'. The channel 704 is in communication with a threaded bore containing a manually adjustable valve 708 provided with a handle portion 709.

A stuffing gland 705 surrounds the valve 708 to avoid leakage of oil along the valve member. The valve 708 is adapted to meter oil from the end of the cylinder 93' adjacent the cap 689 and is one factor in regulating the speed of the piston 685 in one period of movement.

A bore is formed in the piston which snugly receives a check valve fitting 714, shown in detail in FIGURE 25, one end of the bore being in communication with a channel 716 which opens into the peripheral recess or chamber 700 in the piston 685. The fitting 714 is formed with a comparatively large bore 718 and channels 719, 720 and 721. Disposed in the bore 718 is a ball check valve 722 which is biased toward closed position by a spring 723. The channel 719 is in communication with the bore 718 and the channel 716. The channels 720 and 721 establish communication between the bore 718 and the region in the cylinder at the left end of the piston 685 as viewed in FIGURE 24.

The ball check valve 722 is arranged to restrict oil flow from the bore 718 into the channels 720 and 721 but permits oil flow in the opposite direction through channels 721, 720, bore 718 channels 719 and 716. The admission

of oil into the recess 695 in the bushing 687 moves the piston 685, rod 97' and ram 40' in a forward stroke viz. in a left-hand direction as viewed in FIGURE 24. The movement of the piston 685 in the first range, from its initial position illustrated in FIGURE 24, is at a comparatively high rate of traverse.

During this period the cam follower has moved through the distance designated 670' indicated in FIGURE 32. During this period of movement of the piston 685, oil under pressure is admitted through the passages 690, 692, 693 as permitted by the position of the slideable valve 556 shown in FIGURE 4. During this period of movement of the piston, the channel 697 through the valve 556 is connected with a return oil line to the reservoir 194 shown in FIGURE 1.

As this channel is unrestricted, the oil at the left-hand of the piston as viewed in FIGURE 24 is discharged through the channel 697 substantially unrestricted to effect high speed traverse during the distance indicated at 670' in FIGURE 32. When the piston reaches a position covering the entrance to the channel 697 shown in FIGURE 24, the flow of oil from the left-hand of the piston is then metered out through the channel 704 past the metering valve 708 and channel 698 into the return oil line to the reservoir 194, as the check valve unit 725 in channel 702 blocks oil flow out of the cylinder through channel 702.

Thus, the piston 685 is moved at a comparatively slow speed or traverse through the distance indicated by 672' on FIGURE 32. During this movement, the metal disintegrating wheel or electrode 585 is moving adjacent the face 672" of a tooth T of the cutter C, shown in FIGURE 33, to conform this face to the desired shape.

When the piston 685 reaches a position in which the port of the channel 697 registers with the peripheral recess 700 in the piston, the piston is moved at a high rate of traverse as the oil in the cylinder at the left-hand of the piston not only moves out through the metering channel 704 but also elevates or opens the ball check valve 722 in the piston facilitating substantially unrestricted oil flow through channels 721, 720, 719, 716 through recess 700 and channel 697 to the return line to the reservoir.

Hence, throughout the remainder of movement of the piston 685 toward the end plate 689 of the cylinder, the piston moves at a high rate of traverse and no metal removal is taking place during this period as the metal disintegrating wheel or electrode is moved away from the other face 678" of the tooth T of the cutter C, as this face is shaped upon a return stroke of the ram 40. This phase of fast traverse of the ram is indicated at 678' in FIGURE 32.

Upon the start of the return stroke of the piston 685 and the ram 40', a period of slow traverse takes place during which period the face 678" of the tooth T is shaped or configurated by the electrolyte and metal disintegrating electrode wheel 585. When the piston 685 approaches its extreme left-hand position as viewed in FIGURE 24, the abutment or stop member 574 on the rod 570, shown in FIGURE 4, which is moved with the ram, engages the member 576 on the valve shaft 560 shifting the valve 563 to a position directing oil under pressure against the opposite end of the slideable valve 556 to move the latter to the opposite end of the bore 554, shown in FIGURE 4.

The movement of the valve 556 connects the channels 697 and 698, shown in FIGURE 24, with the oil pressure supply line and connects the channels 692 and 693 with the oil return or waste line to the reservoir. In this position, oil under pressure is metered or restricted past valve 708 and through channel 703 into the cylinder 93' at the left-hand of the piston. The valve 708 is adjusted to admit oil under pressure into the cylinder at the rate desired for the slow traverse movement of the piston.

The initial phase of movement of piston 685 in its retractive direction, that is, a right-hand direction as viewed

in FIGURE 24, is at slow traverse because the check valve unit 725 blocks the flow of oil from the recess 700 in the piston and the oil under pressure now existent in the channel 697 is prevented from flowing through the piston channels by the check valve 722 and the port provided by channel 702 is blocked by the piston wall.

When the piston retracts to a position uncovering the port 701 of the channel 702, the pressure of oil in channel 702 effects oil flow past the check valve unit 725 to increase the flow of oil into the cylinder 93'. By thus increasing the rate of flow of oil into the cylinder 93' the piston is moved through the remainder of its retractive stroke at a high traverse speed through the distance indicated at 670a on FIGURE 32 to its initial or extreme right-hand position.

As the piston approaches this position, the abutment 574 on the rod 570 engages the projection 576 on the valve shaft 560, rotating the valve 563 and thereby directing oil under pressure to the opposite end of the cylinder 554 containing the slideable valve 556. This action directs oil under pressure through channels 692 and 693 into the right-hand end of the cylinder 93' and connects the channels 697 and 698 with the return oil line to the reservoir, and a succeeding series of fast and slow traverse movements of the piston 685 occur as above described.

The mounting of the control cam 340 shown in FIGURES 15 and 16 and the action of shifting the cam through a small lengthwise distance with each movement of the ram 40' renders possible the shaping of the face 672" of the cutter during the forward stroke of the ram and the shaping of the face 678" of the cutter during the retractive stroke of the ram. As will be noticed in FIGURE 33, a radius 680 joins the two cutter faces 672" and 678".

The contouring of the cam 340 coupled with lengthwise shifting makes possible the formation of the radius 680 on the cutter tooth T whereby one-half of the radius 680 is fashioned during the shaping of the cutter face 672" and the other half during the shaping of the face 678".

The apex region 676 of the cam 340 is fashioned with a short land joined with the face 672 of the cam by a radius to generate one-half the radius 680 on the cutter tooth T.

The land is joined with the cam face 678 by a radius to generate the remaining one-half of the tooth radius 680. The horizontal land or flat surface at the apex 676 of the cam is equal in length to the lengthwise distance through which the cam 670 is moved at each stroke of the ram 40.

Thus, on the initial cutting or metal disintegrating stroke of the electrode wheel 585 to shape or sharpen the cutter face 672", one-half of the radius 680 is also imparted to the cutter tooth C. The flat surface or land is engaged by the follower 327' and guides the path of the wheel 585 a slight distance beyond the face 678" so that during further movement of the follower 327' along the cam face 678, the wheel 585 is spaced a sufficient distance from the cutter tooth so that no metal disintegration or removal is effected.

This occurs during the ram traverse period indicated at 672' on FIGURE 32. When the ram reaches the end of a stroke, the cam 340 is shifted in the opposite direction so that upon return stroke of the ram, the cutter surface 678" is shaped or formed together with one-half radius 680. The flat surface on land at the apex 676 on the cam guides the follower 327' maintaining the electrode wheel 585 at a distance from the cutter surface 672 so that no further metal removing or disintegrating action takes place during the return stroke of the ram.

FIGURES 26 through 29 illustrate a counting or integrating means arranged to stop the operation of grinding by an abrasive wheel 72 of FIGURE 1 or by the metal disintegration method and arrangement of FIGURE 19 after all of the teeth of a cutter have been shaped or processed by the abrasive grinding wheel or electrode

metal disintegrating means. A plate 702 is adapted to provide mounting means for the ram stroke counting unit and is adapted to be secured to the rear portion of the base frame 10 of the machine by screws 702' received in openings in the plate 702.

The counting unit 704 includes a cylindrically-shaped housing 704' which is secured to the plate 702 by screws 706, one being shown in FIGURE 28. A cylindrically-shaped member 709 is secured to the housing by means of suitable screws. Integrally formed on the housing 704' is a transversely extending boss portion 710 provided with a bore 711 in which is reciprocally mounted a plunger 712 formed with rack teeth 713. Secured to one end of the boss portion 710 is a fitting 715 which is held in assembled relation with the portion 710 by means of screws 715'.

The fitting 715 is formed with a threaded portion 720, the thread of which is preferably of square cross-section character. Rotatably supported on the fitting 715 is a cylindrically-shaped member 726 having an interiorly threaded portion adapted to cooperate with the threaded portion 720 of the fitting 715.

Secured in the outer end of the cylindrical member 726 is a head 727 provided with a rod 728 extending through an axial bore formed in the fitting 715, the portion of the rod extending into the bore 711 being provided with a stop means, abutment or head 729.

With particular reference to FIGURE 26, it will be seen that the region adjacent the inner end of the cylindrical member 726 is provided with an index line 730. The adjacent exterior surface of the cylindrical member 726 being tapered as shown in FIGURES 26 and 27, the tapered region being provided with a series of graduations 732 each representative of a tooth in a cutter to be processed by grinding or metal disintegration. The opposite end of the bore 711 is closed by a cap 734.

Disposed within a bore formed in the housing 705 is an annular member 736, a bushing 737 and a second bushing 738. Mounted within the bushings 737 and 738 is a hub structure 740 which is fashioned with two overrunning or one-way clutch units. One of the units is shown in detail in FIGURE 29 and includes bores formed in the hub 740 accommodating plungers 742 engaging clutch rollers 743, springs 744 biasing the rollers 743 into contact with the surface of a bore formed in a gear 748, the teeth 749 of which are in mesh with the rack teeth 714.

The biasing forces of the springs acting on the rollers 743 are in directions to cause the hub 740 to be moved with the gear 748 when the gear is moved in a counter-clockwise direction as viewed in FIGURE 29.

A similar clutch roller arrangement is carried by the portion of the hub structure adjacent the bushing 737 but the plunger and roller units are arranged in the opposite angles to those shown in FIGURE 29.

The clutch unit adjacent the bushing 737 is adapted to lock the hub 740 during retractive movement of the plunger 712. Mounted within a bore in the cylindrically shaped member 708 is a spacer bushing 752 and disposed in a counterbore in the member 708 is a stuffing gland 754 to prevent leakage of fluid along the bushing 752. Positioned within bores formed in the hub structure 740 and the bushing 752 is a shaft or rod 755 having a frusto-conically shaped portion 756 adapted to mate with a reciprocally shaped interior surface formed in the right-hand end region of the hub structure 740 as viewed in FIGURE 29.

The shaft 754 is formed with an enlarged cylindrically shaped portion 758 which is disposed in the bore of the bushing 736. Formed in the housing 705 is a fluid chamber 760 which is in communication with a port 762 formed in the bushing 736. As shown in FIGURE 28, the enlarged cylindrical portion 758 is provided with a transversely extending slot 764 which is in communication with a bore 765 formed axially in the enlarged portion 758.

The plate 700 is formed with a threaded opening to receive the threaded end of a tube 767 which is connected with the pressure fluid supply provided by the fluid pump 196. The plate 700 and the wall region of the housing 705 defining the chamber 760 are formed with communicating channels 769, the channel in plate 700 being threaded to accommodate an outlet tube 770 which is connected with a pressure operating switch mechanism shown in FIGURES 17 and 18 and hereinafter described.

- 10 Mounted upon the shaft 754 exteriorly of the cylindrical member 708 is a disc-like member 772 secured on the shaft by a key 773. The member 772 is provided with a radially extending projection 774 and the member 708 is provided with an abutment or pin 775 as shown in FIGURE 26. The end region of the shaft 754 is threaded as at 777 to receive a knurled disc or handwheel 778, rotation of the disc 778 moving the shaft 754 into or away from wedging engagement of the frusto-conically shaped portion 756 with the hub structure 740.
- 15 The boss portion 710 adjacent each end region is provided with a threaded opening to respectively receive tubes 780 and 781 for conveying oil or other fluid under pressure into and away from the bore 711 containing the plunger 712. The tube 780 is connected with the channel 578 shown in FIGURE 4, and the tube 781 is connected with the channel 579 shown in FIGURE 4. Thus, at each reciprocation of the ram and hence each reciprocation of the valve 556, oil under pressure is introduced alternately by tubes 780 and 781 into the chamber 711 causing reciprocatory movements of the plunger 712.

A cutting stroke or metal disintegrating stroke is completed on each tooth of a cutter during one complete reciprocation of the ram, and the arrangement illustrated in FIGURES 26 through 29 is adapted to be preset so as 35 to stop or interrupt the operation of the ram after all the teeth of a cutter have been ground, shaped or processed.

Prior to the grinding or metal disintegration of teeth of a cutter, the operator rotates the drum or cylindrical member 720 until the graduation of the series of graduations 732 corresponding to the number of teeth on the cutter is moved into registry with the index 728 on the fitting 715. For example, if there are twenty teeth in the cutter being processed, the graduation 20 is set in registry with the index 728. This adjustment of the drum 720 through the medium of the threads 718 and 721 moves or positions the abutment 726 relative to the right-hand end of the plunger 712.

Thus, during each reciprocatory movement of the ram, 50 the valve 556, shown in FIGURE 4, directs oil under pressure alternately through pipes 780 and 781 into the ends of the bores 711 causing the plunger 712 to complete a reciprocation during each cycle of the ram. The operator releases the finger grip wheel or handwheel 778 and moves or rotates the disc 772 to engage the radially extending abutment 774 with the pin 775 shown in FIGURE 26.

This movement positions the shaft 754 shown in FIGURE 28 so that the slot 764 is out of registry with port 762, this being an initial position of the shaft. The operator then tightens the wheel 778 to frictionally lock the tapered portion 756 of the shaft 754 with the hub structure 740.

When the ram 712 is moved in a right-hand direction 65 as viewed in FIGURES 27 and 29, the gear 748 is rotated through a partial revolution, the extent of which is determined by the stroke of the plunger 712 and its engagement with the abutment 726. The partial rotation of the gear 748 causes the same extent of rotation of the hub structure 740 and the shaft 754. During retractive movement of the plunger 712, the overrunning clutch unit arranged between the bushing 737 and the hub structure 740 prevents reverse rotation of the shaft 754 and the hub structure 740.

Hence, at each movement of the ram in one direction,

the plunger 712 moves the gear 748 through a partial rotation until the shaft 755 has been moved to a position wherein the slot 764 registers with the port 762 shown in FIGURE 28. At this point all of the teeth of the cutter have been ground or processed and fluid under pressure from the supply flows through the slot 764, port 762, chamber 760 and tube 770 to actuate the cut-off switch mechanism shown in FIGURES 17 and 18.

FIGURES 17 and 18 illustrate a form of circuit interrupting switch for the circuit of the motors driving the grinding or electrode wheel and the oil pressure pump 196, which is adapted to be moved to circuit interrupting position by fluid pressure upon completion of the processing operations on all of the teeth of a cutter. Secured to the frame 10 of the apparatus is a plate 790 having outwardly extending spaced wall portions 792 and 793.

Mounted upon the plate 790 is a switch housing 794 containing a circuit interrupting switch connected in circuit with the motor 46 which rotates the grinding or metal disintegrating wheel and the motor 198 driving the pump 196 for establishing fluid pressure in the hydraulic system. The switch construction enclosed in casing 794 includes a movable plunger 796.

Also supported upon the plate 790 is a generally cylindrically shaped member 798 provided with a cylindric bore 800 in which is slidably disposed a piston 802. The piston is provided with a restricted passage 804 facilitating restricted flow of oil for a purpose hereinafter explained. The wall 792 serves as a head for the cylinder or member 798, the wall being formed with a port 806 establishing communication between the tube 770 and the interior of the bore 800 above the piston 802.

An expansive coil spring 808 surrounds a plunger or rod 810 secured to the piston, the rod being aligned with the plunger 796 of the switch contained in the housing 794 whereby downward movement of the piston 802 and the rod 810, as viewed in FIGURE 18, effects engagement of the rod with the plunger 796 to actuate the circuit interrupting switch. An outlet port 812 in the wall of the housing 798 is connected by means of a tube 814 with the oil return line connected with the oil return fitting 203. An oil ring or oil seal 815 is contained in a recess in the plunger 810 to prevent leakage of oil from the cylinder or housing 798.

During the successive movements of the shaft 755, shown in FIGURE 29, under the influence of the reciprocations of the ram, the slot 764 in the shaft 755 is out of registration with the port 762 until the completion of the grinding or processing of the last tooth in the cutter. At the last movement of the shaft 755, the slot 764 registers with the slot-like port 762 facilitating flow of oil under pressure from the pressure pipe or line 767 into pipe 770 through the port 806 shown in FIGURE 18, the oil pressure moving the piston 802 downwardly against the compression of the spring 808, engaging the plunger 810 with the plunger 796 to operate the circuit interrupting switch in the housing 794.

It should be noted that the pressure relief passage 804 in the piston 802 is of lesser area than the port 806 so that a substantial amount of oil enters the cylinder 800 against the piston to move the latter to actuate the circuit interrupting switch.

The purpose of the vent or relief passage 804 is to facilitate restricted flow of oil from the region above the piston to the oil return line so that after a short period of time the oil above the piston flows through the relief passage 804 under the influence of the compression of the spring 808 to return the piston to its initial position, shown in FIGURE 18, after the same has actuated the circuit interrupting switch.

The switch in the housing 794, being of the spring biased type of conventional character, is thus returned to circuit closing position in preparation for the performance of operations on a succeeding cutter placed upon the support 130. The circuit interrupting switch in the

housing 794 is interlocked with a solenoid-held switch means (not shown) which is released by activation of the switch in housing 794 and which is manually moved by the operator to initiate a succeeding cycle of operations upon a cutter.

The hydraulic system for actuating the various components of the apparatus is illustrated schematically in FIGURE 30 and will be explained in describing the operation of the apparatus. When it is desired to contour or resharpen the teeth of a cutter, the cutter is mounted on the spindle 130 shown in FIGURE 1 if the grinding is to be accomplished by an abrasive wheel 72 or on the spindle 130 shown in FIGURE 19 where the cutter teeth are to be configurated or processed by the electrolytic metal disintegrating system.

As the hydraulic actuated components of the apparatus are substantially identical for both forms of apparatus, a description of the operation of the abrasive grinding in accordance with the arrangement shown in FIGURE 1 in conjunction with the hydraulic system shown in FIGURE 30 will suffice. The operator draws up the bolt 137 to hold the cutter in operative position. In positioning the cutter on the support 130 the operator engages one of the cutter teeth with the lip rest 855 to initially position the cutter so that the teeth are in proper relation to be ground by the wheel.

The operator then rotates or adjusts the cylindrical member or drum 720 shown in FIGURE 26 with the graduation corresponding to the number of teeth in the cutter in registration with the index 728. This action positions the abutment 726 shown in FIGURE 26 for predetermining the length of stroke or reciprocation of the plunger 712. This mechanism is, in effect, a counter for counting the number of teeth for the purpose of stopping the operations after all the teeth have been ground or processed.

If the apparatus of FIGURES 1 and 2 is utilized for sharpening the teeth by abrasion with an abrasive wheel, the grinding wheel is automatically fed downwardly at each stroke of the ram to dress the wheel after each grinding operation. The operator adjusts the feed by rotating the cylindrical member 272, shown in FIGURE 5, to a position indicated by the graduations 274 to establish the extent of dressing the wheel.

The operator closes a starter switch mechanism 880 of conventional character for energizing the motors 46 and 198. The operator then moves the handle 104 shown in FIGURE 1 to rotate the valve 102 into a position wherein oil under pressure is metered out of the cylinder 93 to move the piston 98 of the arrangement shown in FIGURE 1 or the piston 685 in the arrangement illustrated in FIGURES 19 and 24, the latter being the arrangement employed when the electrolytic metal disintegration system is used for sharpening or contouring teeth of a cutter. The piston 98 reciprocates the ram 40 carrying the grinding head or metal disintegrating units. The abutments 572 and 574 mounted on the rod 570 and movable with the ram 40 alternately engage and actuate valve 563, shown in FIGURE 4, which effects flow of oil under pressure to hydraulically move the valve 556 shown in FIGURE 4. The alternate movement of valve 556 from one position to another as viewed in FIGURE 4 controls flow of oil under pressure out of the respective ends of the cylinder 93 to automatically reciprocate piston 98 and ram 40.

Actuation of the hydraulic valve 500, shown in FIGURE 3, which controls flow of oil under pressure to the pistons of the index unit 190 and the index return unit 188 illustrated in FIGURE 1 to successively index the spindle 130 supporting a cutter, the teeth of which are to be ground or processed. Each stroke or movement of the valve 500 also effects reciprocation of the plunger 712 of the timer mechanism illustrated in FIGURES 26 through 29.

The reciprocations of the plunger 712 of the timer or

counter mechanism 704 effect successive rotative movements of the valve shaft 755 shown in FIGURE 29 until the port 764 shown in FIGURE 29 is in registration with the port 762 to establish oil flow under pressure through the tube 770 to the cylinder 798 to actuate piston 802, the latter actuating the limit switch 794 to interrupt the circuit to the motors 46 and 198 to stop the apparatus at the completion of the grinding or processing of all of the teeth in a cutter.

When the apparatus illustrated in FIGURE 19 is employed with the electrode wheel 585 for shaping or contouring cutter teeth by electrolytic action, the shiftable cam arrangement shown in FIGURES 15 and 16 is employed in conjunction with the piston and valve arrangement shown in FIGURES 24 and 25 to effect alternate fast and slow rates of speed of the ram 40'. The cam 340 is shifted in alternate directions by admission of oil under pressure alternately through the passages 364 and 368, shown in FIGURE 15, from the control valve mechanism shown in FIGURE 4. The operation of the shiftable cam 340 has been hereinbefore described.

The hydraulic lifting jack 378 is employed whether the apparatus is used for abrasive grinding or with the electrolytic metal disintegration system. The operation of the lifting jack has been previously described herein.

It should be noted that when the apparatus is utilized for electrolytic metal disintegration, the feed mechanism shown in FIGURE 5 is not required as it is unnecessary to engage the electrode wheel with a truing tool or diamond as is necessary with the use of an abrasive wheel. The feed mechanism, shown in FIGURE 5, may be removed from the apparatus when electrolytic disintegration is desired, or the feed mechanism may be rendered ineffective by swinging the arm 300 upwardly out of the path of reciprocation of the plunger 280. When the apparatus is employed for electrolytic metal disintegration the electric energy flows through the brush holder 650, the brushes carried thereby, the shafts or shaft portions 637, 612, 605, through the electrode wheel 585, the electrolytic at the region between the electrode wheel and the tooth of the cutter being processed, the cutter support 130 and cable 161 to a current supply.

It is apparent that, within the scope of the invention, modifications and different arrangements may be made other than as herein disclosed, and the present disclosure is illustrative merely, the invention comprehending all variations thereof.

I claim:

1. In a metal working apparatus, in combination, a base frame, a work piece supporting arbor mounted by the base frame, means for indexing the arbor to successive positions, a supplemental frame mounted by the base for pivotal movement relative thereto, a ram reciprocably mounted on the supplemental frame, a head carried by the ram and arranged for movement relative thereto in a direction normal to the longitudinal axis of the ram, a rotatable metal processing wheel journally supported by the head, hydraulically actuated means for reciprocating the ram, means for rotating the wheel, cam means associated with said ram for effecting relative pivotal movements of the supplemental frame and said ram for guiding the processing wheel into cooperative relation with the workpiece, and means including rack and pinion mechanism arranged between the supplemental frame and the head for effecting movement of the head relative to the ram at each reciprocation of the ram.

2. In a metal working apparatus, in combination, a base frame, a work piece supporting arbor mounted by the base frame, means for indexing the arbor to successive positions, a supplemental frame mounted by the base for movement relative thereto, a ram reciprocably mounted on the supplemental frame, hydraulically actuated means for reciprocating the ram, a head carried by the ram and arranged for movement relative thereto in a direction nor-

mal to the longitudinal axis of the ram, a rotatable metal processing wheel journally supported by the head, means for rotating the wheel, cam means associated with said ram for effecting relative movements of the supplemental frame and said ram for guiding the processing wheel into cooperative relation with the work piece, means including a reciprocable rack member and pinion for effecting movement of the head relative to the ram during each reciprocation of the ram, an abutment arranged to be

5 engaged by said reciprocable rack member to limit the movement of the rack member in one direction of reciprocation, means for adjusting the initial position of the rack member relative to the head to regulate the extent of movement of the head relative to the ram at each reciprocation of the ram.

3. In a metal working apparatus, in combination, a base frame, a work piece supporting arbor mounted by the base frame, means for indexing the arbor, a supplemental frame pivotally mounted by the base, a ram reciprocably mounted on the supplemental frame, hydraulically actuated means for reciprocating the ram, a head carried by the ram and arranged for movement relative thereto in a direction normal to the longitudinal axis of the ram, a rotatable metal processing wheel journally supported by the head, means for rotating the wheel, cam means associated with said ram for effecting pivotal movement of the supplemental frame and said ram for guiding the processing wheel into cooperative relation with the work piece, means including a reciprocable rack

20 member for effecting movement of the head relative to the ram during each reciprocation of the ram, a pivotally supported abutment arranged to be engaged by said reciprocable rack member, means for adjusting the initial position of the rack member to limit movement

25 of the rack member in one direction to regulate the extent of movement of the head at each reciprocation of the ram, said abutment being pivotally movable to a position out of the path of the rack member to eliminate movement of said head relative to the ram.

4. In a metal working apparatus, in combination, a base, an arbor rotatably mounted by the base and adapted to support a work piece, a reciprocable tubular ram, a supplemental frame member pivotally mounted by the base, said member having bearing means supporting said ram for reciprocatory movement, a rotatable metal processing element mounted by the ram, a motor, means disposed within and extending lengthwise of the ram and driven by the motor for rotating the metal processing element, means for reciprocating the ram, cam means for controlling the path of reciprocating movement of the element reciprocated by the ram, means for indexing the arbor to rotate the work piece to move successive portions thereof in position to be processed under the influence of the rotatable element, and means actuated by movement of the ram for intermittently supplying lubricant to the bearing means supporting the ram.

5. Apparatus for processing toothed cutters including, in combination, a frame, means mounted by the frame for supporting a cutter, a ram supporting member pivoted on the frame, a ram reciprocably mounted in bearings carried by said member, a rotatable shaft journally supported by the ram, a rotatable element mounted on the shaft for processing the teeth of a cutter during reciprocatory movements of the ram, hydraulically actuated means for the reciprocating said ram, a housing mounted on the ram supporting member having a bore formed therein, a plunger in said bore, abutment means on said ram engageable with the plunger in said casing to effect reciprocation of said plunger concomitantly with reciprocation of said ram, and means actuated by said plunger for metering the delivery of lubricant to the bearings supporting said ram.

6. In a metal working apparatus, in combination, a base, an arbor rotatably mounted by the base and adapted to support a work piece, a reciprocable tubular ram, a

supplemental frame pivotally mounted by the base, said supplemental frame having bearing means supporting said ram for reciprocatory movement, a rotatable metal processing element mounted by the ram, a motor, means disposed within and extending lengthwise of the ram and driven by the motor for rotating the element, hydraulic means for reciprocating the ram, cam means for controlling the path of reciprocating movement of the element under influence of the ram, means for indexing the work piece supporting arbor to rotate the work piece to move successive portions thereof in position to be processed under the influence of the rotatable element, means actuated by said ram for intermittently supplying lubricant to the bearing means supporting the ram, a counter actuated concomitantly with reciprocatory movements of the ram, means for adjusting the counter to correspond with the number of portions of a work piece to be processed, and means under the influence of said counter arranged to interrupt reciprocatory movement of the ram upon completion of processing operations on a work piece.

7. In a metal working apparatus, in combination, a base, an arbor rotatably mounted by the base and adapted to support a work piece, a reciprocable tubular ram, a supplemental frame pivotally mounted by the base, said supplemental frame having bearing means supporting said ram for reciprocatory movement, a rotatable metal processing element mounted by the ram, a motor, means disposed within and extending lengthwise of the ram and driven by the motor for rotating the element, hydraulic means for reciprocating the ram, cam means for controlling the path of reciprocating movement of the element under influence of the ram, hydraulically actuated means for indexing the arbor to rotate the work piece to move successive faces thereof in position to be processed under the influence of the rotatable element, a counter arranged to be actuated concomitantly with each reciprocation of the ram, means for adjusting the counter to correspond with the number of portions of a work piece to be processed, and means under the influence of said counter arranged to interrupt reciprocatory movement of the ram upon completion of processing operations on a work piece.

8. In a metal working apparatus, in combination, a base frame, a supplemental frame pivotally mounted by the base frame, a reciprocable ram supported by said supplemental frame, hydraulically actuated means for reciprocating the ram, a work supporting arbor rotatably carried by the base frame, a work processing wheel rotatably supported by the ram, cam means controlling the relative pivotal movement of the supplemental frame and ram about the pivotal axis of the supplemental frame during reciprocatory movements of the ram, and hydraulically actuated means for moving said supplemental frame and ram about the pivotal support of the supplemental frame out of the influence of said cam means.

9. In a metal working apparatus, in combination, a base frame, a supplemental frame pivotally mounted by the base frame, a reciprocable ram supported by said supplemental frame, means for reciprocating the ram, a rotatable work supporting arbor carried by the base frame, a work processing wheel rotatably supported by the ram, cam means arranged between the base frame and the ram controlling the relative pivotal movement of the ram about the axis of the supplemental frame during reciprocatory movements of the ram, hydraulically actuated means for pivotally moving said supplemental frame and ram about the pivotal support of the supplemental frame out of the influence of the cam means, said hydraulically actuated means including a cylinder and piston, fluid inlet and outlet ducts for said cylinder, and valve means for controlling fluid flow into said cylinder.

10. In a metal working apparatus, in combination, a base frame, a supplemental frame pivotally mounted by the base frame, a reciprocable ram supported by said

supplemental frame, means for reciprocating the ram, a rotatable work supporting arbor carried by the base frame, a work processing wheel rotatably supported by the ram, cam means arranged between the ram and the base frame controlling the relative pivotal movement of the ram about the axis of the supplemental frame during reciprocatory movements of the ram, hydraulically actuated means for pivotally moving said supplemental frame and ram about the pivotal support of the supplemental frame out of the influence of the cam means, said hydraulically actuated means including a cylinder and piston, fluid inlet and outlet ducts for said cylinder, a valve in said inlet duct for controlling fluid flow into said cylinder, and a restriction in said outlet duct for metering fluid flow out of the cylinder when said valve is closed to retard pivotal movement of the supplemental frame and ram to a position to be influenced by the cam means.

11. In a metal processing apparatus, in combination, a base frame, a work piece supporting arbor mounted by the base frame, a supplemental frame mounted for relative pivotal movement by the base frame, a reciprocable ram supported by the supplemental frame, a work piece processing wheel rotatably supported by said ram, cam means and cam follower means arranged between the ram and base frame for controlling the path of movement of the ram and wheel during reciprocatory movement of the ram, the initial position of one of said means being arranged to be moved relative to the other means, and means activated at each reciprocatory movement of the ram for effecting relative initial movement between said cam means and said cam follower means.

12. In a metal processing apparatus, in combination, a base frame, a work piece supporting arbor mounted by the base frame, a supplemental frame pivotally mounted by the base frame, a reciprocable ram supported upon the supplemental frame, a work piece processing wheel rotatably supported by said ram, cam means and cam follower means for controlling the path of movement of the ram and wheel during reciprocatory movement of the ram, the initial position of one of said means being arranged to be moved relative to the other means, hydraulically actuated means activated at each reciprocatory movement of the ram for effecting relative initial movement between said cam means and said cam follower means, and valve means for varying the rate of reciprocation of the ram.

13. In a metal processing apparatus, in combination, a base frame, a work piece supporting member mounted by the base frame, a supplemental frame mounted for movement relative to the base frame, a reciprocable ram supported upon the supplemental frame, a work piece processing wheel rotatably supported by said ram, a cam, a support for said cam mounted on the base frame, a cam follower carried by said ram and arranged for cooperation with said cam for controlling the path of movement of the ram and wheel during reciprocation of the ram and wheel, hydraulically actuated means for reciprocating the ram, and valve means associated with the hydraulically actuated means for varying the rate of reciprocatory movements of the ram.

14. In a metal processing apparatus, in combination, a base frame, a work piece supporting member mounted by the base frame, a supplemental frame pivotally mounted by the base frame, a reciprocable ram supported upon the supplemental frame, means for reciprocating the ram, a work piece processing wheel rotatably supported by said ram, a cam, a support for said cam, a cam follower carried by said ram and arranged for cooperation with said cam for controlling the path of movement of the ram and wheel during reciprocation of the ram and wheel, relatively movable piston means mounted by said cam support for shifting the position of said cam relative to said cam follower, and means set into operation by the relative position of the ram for directing fluid under pressure against the piston means to shift the relative position of said cam.

15. In a metal processing apparatus, in combination, a base frame, a work piece supporting member mounted by the base frame, a supplemental frame pivotally mounted by the base frame, a reciprocable ram supported upon the supplemental frame, a work piece processing wheel rotatably supported by said ram, a cam, a support for said cam mounted on the base frame, a cam follower carried by said ram and arranged for cooperation with said cam for controlling the path of movement of the ram and wheel during reciprocation of the ram and wheel, relatively movable piston means mounted by said cam support for shifting the position of said cam relative to said cam follower, valve means controlled by the relative position of the ram for directing fluid under pressure against the piston means to shift the relative position of said cam, hydraulically actuated means for reciprocating the ram, and valve means associated with the hydraulically actuated means for varying the rate of reciprocatory movement of the ram.

16. In an apparatus for contouring the teeth of multi-toothed cutters, in combination, a base frame, a supplemental frame supported for relative movement by the base frame, a ram mounted on said supplemental frame for longitudinal reciprocatory movement relative thereto, cam means for guiding the ram during reciprocatory movements to impart relative lateral movements to the supplemental frame and the ram, shaft means carried by said ram supporting a rotatable member for contouring dual cutting regions of the teeth of a multitoothed cutter, means for shifting the relative position of the ram guiding cam means at each reciprocatory movement of the ram whereby movement of the ram in one direction effects a contouring operation on one region of a cutter tooth and movement of the ram in the opposite direction effects a contouring operation on the other region of a cutter tooth, and means for indexing the multitoothed cutter to effect contouring operations on successive teeth.

17. In an apparatus for contouring the teeth of multi-toothed cutters, in combination, a base frame, a supplemental frame pivotally supported by the base frame, a ram mounted on said supplemental frame for longitudinal reciprocatory movement relative thereto, means for guiding the ram during reciprocatory movements to impart pivotal movement to the supplemental frame and the ram, a head carried by said ram, a rotatable member journaled on said head for contouring dual cutting regions of the teeth of a multitoothed cutter, means for shifting the relative position of the ram guiding means whereby movement of the ram in one direction effects a contouring operation on one region of a cutter tooth and movement of the ram in the opposite direction effects a contouring operation on the other region of a cutter tooth, hydraulically actuated means for indexing the multitoothed cutter to effect contouring operations on successive teeth, and hydraulically actuated limit switch means for automatically interrupting reciprocatory movement of the ram at the termination of contouring operations on the teeth of the multitoothed cutter.

18. In a metal working apparatus, in combination, a base frame, a work piece supporting arbor mounted by the base frame, insulating means between the work piece supporting arbor and the base frame, hydraulically actuated means for indexing the arbor, a supplemental frame pivotally supported for relative movement on the base frame, a reciprocable ram mounted on the supplemental frame, 60

an electrode wheel rotatably supported by the ram, means insulating the wheel from the ram, driving means for the electrode wheel insulatingly supported by the ram, means for conducting electric current to said arbor and said electrode wheel driving means, means for flowing an electrolyte onto the electrode wheel to complete an electric circuit through the wheel to the work piece to electrically remove metal from the work piece during reciprocatory movements of the ram.

19. In a metal working apparatus, in combination, a base frame, a work piece supporting arbor mounted by the base frame, insulating means between the arbor and the base frame, means for indexing the arbor, a supplemental frame pivotally mounted by the base frame, a reciprocable ram mounted on the supplemental frame, an electrode wheel rotatably supported by the ram, means insulating the wheel from the ram, driving means for the electrode wheel insulatingly supported by the ram, means for conducting electric current to said arbor and said electrode wheel driving means, means for flowing an electrolyte onto the electrode wheel to complete an electric circuit through the wheel to the work piece to electrically remove metal from the work piece, cam means disposed between the ram and the base frame influencing the path of reciprocation of the ram to control the relative positions of the electrode wheel with respect to the work piece, and hydraulic means for effecting reciprocation of the ram.

20. In a metal working apparatus, in combination, a base frame, a work piece supporting arbor mounted by the base frame, insulating means between the arbor and the base frame, means for indexing the arbor, a supplemental frame pivotally mounted by the base frame, a reciprocable ram mounted on the supplemental frame, an electrode wheel rotatably supported by the ram, means insulating the wheel from the ram, driving means for the electrode wheel insulatingly supported by the ram, means for conducting electric current to said arbor and said electrode wheel driving means, means for flowing an electrolyte onto the electrode wheel to complete an electric circuit through the wheel to the work piece to electrically remove metal from the work piece, a cam support adjacent the ram, a relatively movable cam mounted by the cam support, a cam follower carried by the ram, hydraulic means actuated at each reciprocation of the ram to change the position of the cam relative to its support to control the relative positions of the electrode wheel with respect to the work piece and thereby regulate the periods of effective metal removing action by the electrode wheel and the electrolyte, hydraulic means for effecting reciprocation of the ram, and valve means associated with the ram actuating hydraulic means for varying the rate of reciprocation of the ram.
